United States Patent Office

Des. 188,333
Patented July 5, 1960

188,333

ROLLER SKATE

John Budd, Eastford, Conn., assignor to Union Hardware Company, Torrington, Conn., a corporation of Connecticut

Filed Feb. 24, 1960, Ser. No. 59,495

Term of patent 14 years

(Cl. D34—5)

FIG. 1

FIG. 2

FIG. 3

FIG. 4

Fig. 1 is a perspective view of a roller skate showing my new design;

Fig. 2 is a bottom view thereof;

Fig. 3 is a front elevational view thereof; and

Fig. 4 is a rear elevational view thereof.

The dominant features of my design reside in the portions shown in full lines.

I claim:

The ornamental design for a roller skate, as shown and described.
